UNITED STATES PATENT OFFICE.

WINDER ELWELL GOLDSBOROUGH, OF LA FAYETTE, INDIANA.

ALTERNATING-CURRENT MOTOR.

No. 921,826.

Specification of Letters Patent.

Patented May 18, 1909.

Application filed August 11, 1903. Serial No. 169,149.

To all whom it may concern:

Be it known that I, WINDER E. GOLDSBOROUGH, a citizen of the United States, residing at La Fayette, in the county of Tippecanoe and State of Indiana, have invented certain new and useful Improvements in Alternating-Current Motors; and I do hereby declare the following to be a full, clear, and exact description of the invention, such as will enable others skilled in the art to which it appertains to make and use the same.

My invention relates to alternating current motors in which there is no electrical connection between the primary, or field, coil and the secondary, or armature, coil. And my invention consists in the constructions, combinations, and arrangements hereinafter described and claimed.

In my preferred construction, impedance coils are placed between the coils of the armature or secondary element and a short-circuiting ring, and means provided whereby the inductance of such impedance coils is diminished at suitably located points so as to admit of the ready passage of currents induced in the coils of the armature through said impedance coils, while maintaining the inductance of said impedance coils, at such a value in all other positions as to prevent any great leakage of the armature currents through them.

The generation and distribution of current in the coils of the armature or secondary element are effected entirely by induction; in other words, currents are passed into the coils of the primary element from a single-phase alternating current source of supply, and they so induce currents in the coils of the secondary element that these currents react upon the primary element to produce a torque and the generation of mechanical power through rotation.

In my application for patent filed May 1, 1903, Serial No. 155,172, I have shown and described inductance neutralizing electro-magnets and commutating impedance coils applied to common types of armatures of electrical machines; and also disclosed the adaptation and use in alternating current motors of pole-face coils in combination with field or primary coils for promoting electro-magnetic reactions, which improve the operation of alternating current motors.

My present invention relates to a new and special application of the said inductance

neutralizing electro-magnets, commutating impedance coils and pole-face coils in combination with new and useful improvements in alternating current motors, as fully described hereinafter. In carrying out my invention, I have used various means of securing this result, and the accompanying drawings, forming a part of this application and in which similar reference symbols indicate corresponding parts in the several views, illustrate not the specific construction of any particular device employed, but rather the electrical connections employed with well-known devices.

In the drawings: Figure 1 is a diagrammatic view of one form of alternating current motor, showing clearly the field-coils and pole-face coils of the primary element, the armature coils and impedance coils of the secondary element, and inductance-increasing-electro-magnet-armatures or inductors suitably placed with reference to the impedance coils. In this construction, a field ring having internally projecting poles is used. Fig. 2 shows, diagrammatically, an arrangement of parts similar to those of Fig. 1, except that each impedance coil of the secondary element is wound on a horseshoe core and brought into inductive relation with neutralizing electro-magnets suitably located. Furthermore, as in Fig. 1, means are provided whereby the inductance of the impedance coils is increased during the time of their passage between the inductance neutralizing electro-magnets to a value in excess of the normal impedance of these coils. Fig. 2a illustrates diagrammatically an arrangement employing certain auxiliary devices whereby the primary field coils may be connected in series, and the primary pole face coils also connected in series, and these two series placed in parallel. Fig. 3 shows another arrangement of my invention, the primary element forming the outer portion of the figure, and the secondary element the central portion of the figure. As the connections indicate, every other coil in the primary element is a field coil, while the intermediate coils of the primary element are pole-face or inducing coils. The armature coils and the impedance coils of the secondary element are plainly shown in inductive relation to inductance neutralizing electro-magnets in certain positions. Fig. 4 shows another form of my invention, the primary element being the outer portion of

the figure, and the secondary element the central portion of the figure. Commutating impedance coils are shown inserted in the leads brought out from the coils of the 5 secondary element, and inductance neutralizing electro-magnets are shown superposed over certain of the commutating impedance coils, the leads from which terminate in a short-circuiting ring. Fig. 5 is a diagrammatic view of an alternating current motor, in which two inductance neutralizing electro-magnets are used at each point of inductance neutralization or commutation, one of these inductance neutralizing electro-magnets being brought into inductive relation with the coils of the secondary element 10 at a point between the pole-tips of the primary element in the neutral plane, and the other inductance neutralizing electro-magnets net being placed in inductive relation to the impedance coils in the neutral plane. In this construction, the field coils are wound in slots cut in the pole faces, the armature coils in slots cut in the core of the armature 15 or secondary element, and the impedance coils in slots cut in the common core over which the impedance coils are wound. Between the points of inductance neutralization or commutation, inductors are so arranged as to increase the inductance of the 20 impedance coils during their movement by said inductors. Fig. 6 is a diagrammatic view of a portion of the magnetic circuit of an alternating current motor, similar to that shown in Fig. 5, except that every 25 other slot of the armature or secondary element contains the conductors of the armature or secondary coils, while the intermediate slots contain the conductors of the impedance coils, and above the teeth of 30 the core of the said armature or secondary element in the neutral plane at the point of inductance neutralization is placed an inductance neutralizing electro-magnet. Fig. 45 35 7 is a diagrammatic view of a portion of an alternating current motor, similar to that shown in Fig. 5, the armature or secondary element of which is provided with a double winding. By this arrangement, each slot 40 contains the conductors of an armature or secondary coil, as well as the conductors of an impedance coil. Above the teeth of the armature or secondary element in the neutral plane, and at the point of inductance 45 neutralization or commutation, are shown inductance neutralizing electro-magnets. Fig. 8 illustrates diagrammatically an arrangement of the impedance coils with reference to the inductance neutralizing electro-magnets placed over the said impedance coils. Fig. 9 shows diagrammatically another arrangement of impedance coils, with a superposed coreless inductance neutralizing coil. Fig. 10 is a diagrammatic view of 60 65 an arrangement of parts wherein the in-

ductance neutralizing electro-magnets are made, magnetically, a part of the primary core; wherein connections are provided for reversing the direction of rotation of the secondary element and wherein every other slot 70 of the armature or secondary element contains the conductors of the armature coils, while the intermediate slots contain the conductors of the impedance coils. Fig. 11 is a diagrammatic view of a primary element of a single phase alternating current motor similar to that shown in Fig. 10, and provided with connections whereby the circuits of the neutralizing electro-magnets may be opened, and a connection whereby the circuits of the field 75 or primary element may be rearranged so as to make them effective as the primary circuit of a single phase induction motor. Fig. 12 shows, diagrammatically, an arrangement of my invention whereby the primary element is made to consist of two cores placed side by side, one of these being wound with the primary field coils and the other being wound with what I have termed the primary pole face coils. The armature or 80 secondary element is lengthened so as to present a continuous surface extending in front of both the primary cores. The armature coils and impedance coils of the secondary element are plainly shown, together with the inductance neutralizing electro-magnets suitably placed with reference to the impedance coils. In this figure, the vertical line 12-12 is a section line 85 which cuts off the right half of the front primary core and permits the corresponding half of the rear primary core to be viewed. 90

In my devices, laminated metal should, preferably, be used in the construction of primary and secondary magnetic circuits. 105 Further than this, either the primary or secondary can in any case be made either the rotating or stationary element and the design of the cores modified accordingly.

Referring, especially, to Fig. 1, R designates the field ring, N the north and S the south poles of the primary element of a single phase alternating current motor. J designates the field windings, and K the pole face coils of the primary element. The conductors K^2 of the pole face coils K are so placed relatively to the pole faces as to be brought into inductive relation with the conductors A^2 of the coils A of the armature or secondary element. The secondary element is shown provided with a Gramme ring winding, the coils of which are connected to the short-circuiting ring I through impedance coils B. The field coils J are all connected in series and the pole face coils K are also all connected in series; and, further, the field coils J are connected in series with the pole face coils K, thereby causing the alternating currents which are drawn from the source of supply X^3 to 110 115 120 125 130

traverse all of the primary windings connected in series. The function of the field coils J is to produce a magnetic field varying in its intensity with the pulsations of the 5 alternating currents from the source of supply. The function of the pole face coils K is, by virtue of their position, to induce electric currents in the armature coils A which, by reaction with the magnetic fields 10 of the poles N and S produce relative motion of the surfaces of the primary and secondary elements, since the direction of flow of the currents in the armature coils A is so controlled by the presence of the impedance 15 coils B and the inductors P^3 and P^4 as to prevent the said induced electric currents from entering the short-circuiting ring I appreciably through any of the impedance coils except such as B^2 which are without the 20 influence of the inductors P^3 and P^4 . The pole-face coils are so arranged and connected as to tend to promote the same polarity at the pole tips N^2 and the same opposite polarity at the pole-tips S^2 . It will be seen 25 that the inductors P^3 and P^4 serve to increase the inductance of the impedance coils passing between them.

It is to be understood that Fig. 1 is merely diagrammatical. The armature, pole face 30 and field windings may be given the form of wave or lap windings, or such other common form as may be deemed most effective.

The inductive action of the primary pole 35 face coils K upon the secondary or armature coils A is such as to cause currents to pulsate through the armature windings in such manner as to produce natural points of commutation at or near the neutral planes between the pole tips, as in other forms of 40 commutating electric machines.

It is to be understood that the field and pole face coils may be connected in a variety of ways. The field coils may all be connected 45 in parallel and this parallel system connected in series with a series arrangement of pole face coils, or the field coils, all connected in parallel, may be connected in series with the pole-face coils, also connected in 50 parallel; or other arrangements may be used, as may be found in special cases most effective.

While the alternating current motor is shown equipped with four poles, it is obvious 55 that any even number of poles may be employed, other details, as regards the number of inductors, etc., being arranged in conformity thereto.

Referring to Fig. 2, R designates the field 60 ring or core of the primary element. O the core of the armature or secondary element, and P and C^2 the cores of the impedance coils and neutralizing inductance electro-magnets respectively. In this figure, J^2 , J^4 , 65 J^5 , J^6 , etc., represent the terminals of the

field coils of the primary element, and K^2 , K^4 , K^5 , etc., the terminals of the pole face coils of the primary element. The secondary element, with its coils A , is so placed as to bring the said coils into close inductive relation with the pole face coils of the primary element, and the core O is so placed relatively to the core R that the magnetic pole flux set up by the field coils permeates the core O of the secondary element. I indicates 70 a short-circuiting ring to which one terminal of each of the impedance coils B is connected, the other terminals of these coils being connected to evenly-spaced taps in the winding A of the secondary core O . The inductors P^3 are so placed with reference to the cores P of the impedance coils as to increase the inductance of the impedance coils during all that portion of each revolution in which it is desirable that no current from the 85 armature coils shall flow through the said impedance coils. The inductance neutralizing electro-magnets C^4 are so placed as to react inductively upon the impedance coils B at certain specified points in each revolution 90 where it is desirable that the currents in the armature coils A should communicate and thereby flow through the commutation leads M , which connect the armature coils through the impedance coils to the short-circuiting 95 ring I . The inductance neutralizing electro-magnets C^4 may be advanced or retarded in their positions as shown by the upper and lower magnets C^4 of Fig. 2. In general, the field coils J are so connected as to produce 100 magnetic poles of opposite polarity midway between the points of location of the inductance neutralizing electro-magnets C^4 , and the pole-face coils K are so connected as to tend to produce magnetic poles of opposite 105 polarity at points directly in line with the positions occupied by the inductance neutralizing electro-magnets. To bring about this result, the field coils J may be connected in series with the pole-face coils K , and the 110 primary currents be made to follow the following path: from the source of energy to J^2 ; from J^4 to J^6 ; from J^5 to J^1 ; from J^8 to J^{10} ; from J^9 to K^2 ; from K^4 to K^6 ; from K^5 to K^7 ; from K^8 to K^{10} ; and, finally, from 115 K^9 to the other terminal of the source of energy. By the aid of suitable auxiliary devices,—in the way of condensers E or of impedance coils F placed in series with either the primary field circuit or the primary pole 120 face coil circuit, or both, as conditions make necessary (see E and F , Fig. 2a)—the primary field coils J may be connected in series and the primary pole face coils K also connected in series, and these two series 125 sets placed in parallel, as, for instance: (see Fig. 2a) a circuit from X^2 to E to J^2 ; from J^4 to J^6 ; from J^5 to J^1 ; from J^8 to J^{10} ; from J^9 to the source of supply X^2 may work in parallel with a circuit from X^2 to F to K^6 ; 130

from K^{10} to K^8 ; from K^7 to K^5 ; from K^6 to K^4 ; from K^3 to the source of supply.

In Fig. 3 (as in Figs. 1 and 2), the field core, armature core and impedance coil core are represented by R, O and P respectively. In this figure, the field coils J are shown connected in series with the pole face coils K. Connections are indicated, however, at K^3 , X^3 , J^3 , and J^4 , whereby the current in the field coils may be reversed relatively to the current in the pole face coils, providing the terminals X^2 , K^4 are influenced by a primary source of supply and the existing connections are changed so that current flows between J^4 and K^3 , and X^3 and J^3 . As shown, primary currents permeating the field coils promote magnetic poles of opposite polarity, which have their greatest intensities at N and S, while the currents flowing in the pole face coils tend to promote poles of opposite polarity at N^2 and S^2 .

In Fig. 3, all of the commutating impedance coils B are wound over a common core P, and terminate in the short-circuiting ring I, thereby connecting the armature coils A with the said short-circuiting ring. With this combination, the inductance of the impedance coils is such as to prevent any great interchange of current between the armature coils A and the short circuiting ring I, except at those points where the impedance neutralizing electro-magnets C⁴ are placed. Electro-magnetic reactions occur, which reduce the effective inductance of the impedance coils, and, when the said inductance neutralizing electro-magnets are properly placed with reference to the secondary element, natural points of commutation occur opposite the poles of the said inductance neutralizing electro-magnets. In this motor, as in others herein described, the function of the field coils is to promote magnetic fields, which permeate from the primary into the secondary core; whereas the function of the pole face coils is to induce currents in the armature coils which flow, when properly commutated, in such manner as to react magnetically upon the flux developed by the field coils and thereby promote the rotation of the secondary element relatively to the primary element.

Fig. 4 shows a somewhat different arrangement and combination of parts. In this, as in previous cases, primary currents permeating the field and pole-face windings set up poles of opposite polarity, as indicated, and thereby currents are induced in the coils A of the secondary winding which, in the present instance, are commutated when the impedance coils B, which are connected between the armature coils and the short-circuiting ring I, pass under the inductance neutralizing electro-magnets C⁴. In Fig. 4 one of the inductance neutralizing

electro-magnets C⁴ has been omitted for clearness.

Fig. 5 shows projecting poles surrounded by field coils J, the pole face coils K being arranged in slots cut into pole faces. In this arrangement of parts, two sets of inductance neutralizing electro-magnets are used, one set C being arranged in inductive relation, to the armature coils A at the points of commutation, the second set C⁴ being arranged in inductive relation to the impedance coils B at the points of commutation. For effective working, the points of commutation may be taken midway between the pole tips N² and S², or the position of the inductance neutralizing electro-magnets may be advanced or retarded relatively to the direction of rotation of the secondary element, as may be found necessary. The inductors P² are given the position shown in order that the impedance of the coils B may be increased during the time of their passage between the points of commutation, thereby more perfectly preventing an interchange current between the armature coils A and the short-circuiting bar I. It is not necessary that any given number of coils shall be embraced between the poles of the inductance neutralizing electro-magnets. In Fig. 3, however, a combination is shown giving very effective results.

Fig. 6 illustrates a construction in which the commutation impedance coils are wound over the same core as are the armature coils. In this case, the inductance neutralizing electro-magnet C performs the double service of neutralizing the inductance of the armature coil A² to commutating currents, and of neutralizing the inductance of the impedance coils B² and B² to commutated currents while not affecting the inductance of the impedance coils B² and B² when considered as elements of the commutating circuit of the coil A, which is undergoing commutation. At the time when the armature coil A² is influenced by commutating currents, and at the time when the impedance coils B² and B² are influenced by commutated currents, they each and severally act as primary transformer coils in relation to the short-circuited coil of the electro-magnet C, thereby inducing in the short-circuited coil of the electro-magnet C currents that electro-magnetically balance the commutating currents flowing in the coil A² and the commutated currents flowing in the coils B² and B², thereby effectively neutralizing the inductance of said coils. When the coils B² and B², are influenced by commutating currents, they form elements in the commutating circuit of coil A². The commutating currents flow through coils B² and B² in a way to make their electro-magnetic effect upon the short-circuited coil of the electro-magnet C null and void; conse-

quently, there is no reaction from the short-circuited coil of the electro-magnet C upon the coils B² and B², and their effective impedance, when considered as elements of the 5 commutating circuit, is not changed. By "commutating current" is meant current that circulates through a coil A², and the coils B² and B², then returning through coil A² without in any way affecting any 10 other armature coil; in other words a commutating current is a current that circulates locally in a commutating coil during the time when the commutating coil is undergoing commutation. A "commutated current" is a current that flows from those 15 groups of armature coils that are not undergoing commutation, through the coils B² and B² and the short-circuiting ring I, returning upon itself without at any time flowing 20 through a coil that is actively undergoing commutation.

In Fig. 7 a construction is illustrated in which a double winding is placed on the secondary element O, the armature and impedance coils of the two distinct windings A and A² being placed in very intimate electro-magnetic relation. In this case, the inductance neutralizing electro-magnet C performs the same function for each of the 30 said windings as does the inductance neutralizing electro-magnet C of Fig. 6 for the one winding contained in this figure.

In Figs. 6 and 7, the pole face coils are omitted for clearness.

35 In Fig. 8, the core C is shown covering the ends of the cores P of the impedance coils. By this arrangement, the inductance of the impedance coils is greatly affected, and, as shown, the inductance neutralizing 40 electro-magnets C embrace but two of the commutation impedance coils B. It should be noted that, to make them effective, when placed on projecting teeth, adjacent impedance coils must be wound in opposite directions. The inductance neutralizing electro-magnets may embrace a greater number 45 than two of the impedance coils with effectiveness. The position of the inductance neutralizing electro-magnets may be given an 50 angle of advance or lag, as conditions require.

Fig. 9 illustrates an inductance neutralizing coil with armature and commutation impedance coils wound in the same slots. 55 In this case, the coil C surrounds no iron core, and is therefore brought into inductive relation with the impedance coils B² by an adjustment of turns of the coil C in such near proximity to the impedance coils B² 60 that the flux set up by the said impedance coils will link through the said inductance neutralizing coil.

In special cases, it may be desirable to reduce the coil C to a strip of metal. This 65 arrangement can also be used in connection

with such combinations as those illustrated in Figs. 5, 6 and 7, wherein inductance neutralizing coils are used to effect the inductance, not only of the impedance, but also of the armature coils.

Fig. 10 illustrates a construction in which both the primary and secondary coils are wound in deep slots. In this case, the cores C² of the inductance neutralizing electro-magnets are made part of the primary field 70 core R. In such combination, it is not necessary that the number of primary slots V bear any definite relation to the number of secondary slots W. The field winding is so arranged in combination with the reversing 75 switch Y that the direction of current in the pole-face coils K may be reversed at will by throwing the switch Y to its second position. A reversal of the current in the pole face coils reacts magnetically upon the secondary 80 element to reverse the direction of rotation of the armature O. As diagrammatically indicated, a short-circuiting device is introduced in the secondary winding A, whereby the impedance coils B may 85 be made a part of the armature winding upon closing the short-circuiting switches U. These switches are only closed when the armature or secondary element is in or near synchronism. When so closed, the secondary 90 tends to act as does the secondary of a single phase induction motor.

Fig. 11 illustrates, diagrammatically, a primary element R¹, which may be substituted for the primary element R in the construction shown in Fig. 10. In the construction shown in Fig. 11, when the switches U are closed, the switch Z should be thrown over to its second position, thereby reversing the direction of current in the pole face 100 coils and causing them to act in unison with the field coils. Thus, after reaching synchronism, by reversing the primary pole face connections at Z, and opening the primary switch Z² and closing the secondary 105 switch circuits U, the power of the motor, taken as a single phase induction motor, 110 may be materially augmented.

Fig. 12 represents a combination of parts 115 wherein the primary element consists of two cores, R and R². The first of these carries the polar projections N and S and the field energizing coils J. The second of these carries the pole face coils K and the impedance neutralizing coils C. The secondary element 120 O used in this combination differs from the secondary element which has been described in connection with Fig. 10, only in that it is extended to present an inductive surface to each of the two primary elements. The advantage of this arrangement lies in the fact 125 that, under certain conditions, it is desirable to electro-magnetically insulate the circuits of the field energizing coils J and the pole face coil K. This is best accomplished by 130

6
placing them side by side on separate cores, as indicated. The functions of the field coils J, pole face coils K and inductance neutralizing electro-magnets C is in no wise 5 changed, in view of this new combination.

It is obvious that I may employ in my invention any old combinations of series or parallel adjustment between the field coils and pole face coils, and that the construction 10 of the primary core or the number of poles employed may be varied as desired. It is also clear that I may employ any common type or armature winding, such as lap and wave winding.

15 Having thus fully described my invention, what I claim as new and desire to secure by Letters-Patent of the United States is:

1. In an armature, the combination of 20 armature coils, impedance coils, inductors and short-circuited coils arranged to be a commutator, as set forth.

2. In an alternating current motor, the combination of armature coils, inductors, and impedance coils arranged to be a commutator, as set forth.

3. In an alternating current motor, the combination of armature coils, short-circuited coils, and impedance coils arranged to be a commutator, as set forth.

30 4. In an alternating current motor, the combination of armature coils, impedance coils, inductors and short-circuited coils, as set forth.

5. In an alternating current motor, the combination with field coils and pole face coils of armature coils, impedance coils and inductors, as set forth.

35 6. In an alternating current motor, the combination with field coils and pole face coils, of armature coils, impedance coils and short-circuited coils, as set forth.

40 7. In an alternating current motor, the combination with field coils and pole face coils of armature coils, impedance coils, inductors and short-circuited coils, as set forth.

45 8. In an electric motor, the combination of armature coils, and of means constructed to effect commutation of the electric currents entirely electro-magnetically, and of means constructed to short-circuit the said means which effect commutation, as set forth.

50 9. In an electric machine, the combination of an armature winding provided with commutation leads, of impedance coils introduced into said commutation leads, of armature coils, and of means for bringing adjacent commutation leads into electric connection at points on said commutation leads between said armature winding and said impedance coils, as set forth.

55 10. In an electric motor, the combination of field coils and armature coils, and of induction coils having short-circuited windings arranged in inductive relation to said

armature coils without being in inductive relation to said field coils, as set forth.

11. In an electric machine, the combination of an armature and armature coils, of impedance coils, and of induction coils having short-circuited windings arranged in inductive relation to the said impedance coils, as set forth.

12. In an electric machine, the combination with an armature and armature coils, of impedance coils, and of inductance coils having short-circuited windings arranged in inductive relation to the said armature coils, and of other induction coils having short-circuited windings arranged in inductive relation to the said impedance coils, as set forth.

13. In an electric machine, the combination with an armature and armature coils, of impedance coils and of induction coils having short-circuited windings arranged in inductive relation to the said armature coils and impedance coils, as set forth.

14. In an armature, the combination with an armature core and armature coils, of means constructed to effect commutation of the electric currents entirely electro-magnetically, and means constructed to individually short-circuit said armature coils, as set forth.

95 15. In an alternating current motor, the combination of an armature winding provided with commutation leads, a short-circuiting ring or terminal, impedance coils connected in the commutation leads from said armature winding to said short-circuiting ring or terminal, and inductor-bars suitably arranged with reference to the impedance coils, as set forth.

100 16. In an armature, the combination of a common terminal, tapped circuits terminating at said common terminal, impedance coils connected in each of the tapped circuits, and short-circuited induction coils arranged in inductive relation to the said impedance coils, as set forth.

110 17. In an armature, the combination of a common terminal, tapped circuits containing impedance coils and terminating at said common terminal, and electric conductors arranged in inductive relation to said impedance coils, as set forth.

120 18. In an armature of an electric machine, the combination of armature conductors having a common terminal, and electric conductors arranged in inductive relation to the armature conductors at the points of commutation, as set forth.

125 19. The combination in an electric motor of a primary element and a secondary element, impedance coils, induction coils having short-circuited windings, and inductors, all so constructed and arranged that the direction of flow of currents induced in the secondary conductors will be reversed with

reference to the direction of flow of current in the primary conductors at predetermined points in a revolution of the secondary element, as set forth.

5 20. The combination in an electric motor, of a primary element and a secondary element, impedance coils, and induction coils having short-circuited windings, all so constructed and arranged that the direction of 10 flow of currents induced in the conductor of the secondary element will be reversed with reference to the direction of flow of the current in the primary conductors at predetermined points in a revolution of the second- 15 ary element, as set forth.

21. The combination in an electric motor, of a primary element and a secondary element, impedance coils and inductors, all so constructed and arranged that the direction 20 of flow of currents induced in the conductors of the secondary element will be reversed with reference to the direction of flow of currents in the conductors of the primary element at predetermined points in a revolution 25 of the secondary element, as set forth.

22. In an alternating current machine, the combination of an armature, armature coils provided with leads, a common terminal, impedance coils arranged in the leads from the 30 armature coils to said common terminal, and means for short-circuiting the said leads between the armature coils and the said impedance coils, as set forth.

23. In an alternating current machine, the 35 combination of an armature, armature coils provided with leads, a common terminal, impedance coils introduced into the leads connecting the armature coils with said common terminals, and means for short-circuiting the said leads between the said armature 40 coils and the said impedance coils, all so constructed and arranged that the said impedance coils are made to perform the same function as the said armature coils when the 45 said machine is operated as an induction motor, as set forth.

24. In an alternating current machine, the combination of a primary element, of field coils, and pole face coils thereon connected 50 in series, an armature carrying armature winding provided with commutation leads, a common terminal, impedance coils introduced into the leads connecting the armature winding with said common terminal, 55 means constructed to reverse the current through certain of the pole-face coils, so that they act with the field coils to produce magnetic poles of maximum intensity, and means for short-circuiting the said commutator 60 leads between the said armature winding and the said impedance coils, whereby the said impedance coils are made to perform the same function as the said armature coils, when the said machine is operated as an in- 65 duction motor, as set forth.

25. The combination in an electric motor, of a field-element, field-coils and pole-face coils, an armature element, armature coils provided with commutation leads, impedance coils arranged in said commutation leads, a 70 commutation ring, induction coils having short-circuited windings, and inductors, as set forth.

26. The combination in an electric motor, of a field element, field coils and pole face 75 coils connected in series, an armature element, armature coils provided with commutation leads, a commutation ring, impedance coils arranged in said commutation leads and arranged to terminate in the commutation ring, induction coils having short-circuited windings placed in inductive relation 80 at predetermined points to said impedance coils, and inductors placed in predetermined positions with reference to said impedance 85 coils and said induction coils, as set forth.

27. The combination with a source of electric energy, of an alternating current machine having independent magnetic circuits wound with short-circuited coils arranged, in relation to its armature, in derivation or multiple arc with the normal magnetic circuit or circuits of the said alternating current machine, as set forth. 90

28. In an alternating current motor, the 95 combination with an armature and armature coils, provided with leads containing self-induction, of independent short-circuited elements constructed to be brought into inductive relation with the armature 100 coils and leads containing self-induction, whereby magnetic fluctuations due to variable currents permeating the armature coils and leads containing self-induction are suppressed, as set forth. 105

29. The combination with an armature and armature coils provided with leads having self induction, of conducting elements so disposed with reference to the surface of said armature as to reduce in volume the 110 currents induced in the armature coils when the direction of flow of said currents in said armature coils is reversed at pre-determined points in a revolution of said armature, as set forth. 115

30. The combination of an armature, a common terminal, armature coils provided with commutation leads, the termination of said leads in said common terminal, impedance coils connected in said commutation 120 leads, and iron cores having short-circuited windings arranged to be brought into inductive relation with impedance coils, as set forth.

31. The combination of an armature, a 125 common terminal, armature coils provided with commutation leads the termination of said leads in said common terminal, impedance coils connected in said commutation leads, and iron cores having short-circuited 130

windings arranged to be brought into inductive relation with said armature coils and impedance coils, as set forth.

32. In an alternating current machine, 5 the combination of a common terminal, armature coils provided with commutation leads to said common terminal, and having self-induction, and independent short circuited coils constructed and arranged to diminish the effective self-induction of 10 said leads to commutated currents, while not diminishing the self-induction of said leads to commutating currents, as set forth.

33. The combination with an electric circuit, of an alternating current machine, a 15 common terminal, an armature, armature coils provided with commutation leads to said common terminal, impedance coils connected in series with said commutation leads, 20 means for making the inductance of said impedance coils effective in cutting down the currents induced in said armature coils when they are commutated, and means for making the inductance of said impedance 25 coils ineffective in obstructing the flow of commutated currents through said leads when they form part of commutation circuits, as set forth.

34. In an alternating current machine, 30 the combination of armature coils provided with commutation leads having self-induction, independent electrically short-circuited electro-magnetic circuits arranged in inductive relation to the armature coils, and other 35 independent electrically short-circuited electro-magnetic circuits arranged in inductive relation to the commutation leads whereby the effective self-induction of said armature coils and commutation leads is changed, as 40 set forth.

35. In an alternating current machine, the combination of a common terminal, armature coils provided with commutation leads having self-induction and terminating 45 in said common terminal, short-circuited induction coils arranged within the influence of said armature coils, and other short-circuited induction coils within the influence of said commutation leads, as set forth.

36. The combination in an alternating current machine of armature coils provided with commutation leads, impedance coils connected in said commutation leads, induction coils having short-circuited windings adapted to 55 change the effective self-induction of the armature coils, and other induction coils having short-circuited windings adapted to change the effective self-induction of the impedance coils during the time of the 60 commutation of said armature coils, as set forth.

37. In an alternating current machine, the combination of a common terminal, armature coils provided with leads having self-induction and connecting the said armature 65 coils to said common terminal, iron cores

wound with short-circuited coils placed in inductive relation to the armature coils, and other iron cores wound with short-circuited coils placed in inductive relation to the leads, all constructed and arranged to diminish the volume of the currents induced in the armature coils during the period of commutation, as set forth.

38. In an alternating current machine, the combination of a common terminal, armature coils provided with commutation leads having self-induction and terminating in 70 said common terminal, electro-magnets having short-circuited windings placed in inductive relation to the armature coils, and of electro-magnets having short-circuited windings and placed in inductive relation to the commutation leads, and all constructed and arranged to reduce the effective inductance of the armature coils while increasing 75 the impedance of the closed circuits through the armature coils during their commutation, and to reduce the effective impedance of the commutating circuits through said 80 armature coils, impedance coils, and common terminal, as set forth.

39. The combination with an electric circuit of an alternating current machine, armature coils provided with commutation leads, impedance coils connected in series 95 with said commutation leads, means constructed and arranged to lessen the inductance effect of the said armature coils when they are commutated, means constructed and arranged to render effective the inductance 100 of said impedance coils in cutting down the currents induced in said armature coils when they are commutated, and means constructed and arranged to render the inductance of 105 said impedance coils ineffective to obstruct the flow of currents through such armature coils as are not undergoing commutation, as set forth.

40. The combination with an electric circuit, of an alternating current machine, armature coils provided with commutation leads having self-induction, means constructed and arranged to render the self-induction of the armature coils less effective 110 in inducing currents and to render the self-induction of said commutation leads effective in cutting down the currents induced in said armature coils when they are undergoing commutation, and means constructed and arranged to render the self-induction of 115 said commutation leads ineffective in obstructing a flow of current in such of the armature coils as are not undergoing commutation, as set forth.

41. In a single-phase alternating current 120 motor, the combination of a field or primary core having an energizing circuit constructed to produce adjacent magnetic poles of opposite polarity, and an inducing circuit constructed to convey current in opposite 125 130

directions over the said magnetic poles of opposite polarity, a common terminal, an armature having leads containing self-induction and terminating in said common 5 terminal, and means constructed and arranged to commutate or reverse currents induced in said armature at predetermined points in a revolution of the armature, as set forth.

- 10 42. The combination in a single-phase alternating current motor, of field coils, pole-face coils, armature coils, impedance coils, and short-circuited inductance coils, means constructed and arranged to shift the neutral 15 points in said motor by changes in the connections of said field coils, means constructed to facilitate the commutation of currents in said armature coils, means constructed to short circuit the commutation circuits 20 through the said armature coils, means constructed to reverse the direction of rotation of the motor by changes in the connections of said field and pole-face coils, means constructed to convert the motor into an induction 25 motor by changes in the connections of said field coils, pole-face coils, armature coils and short-circuited induction coils, as set forth.

43. The combination in an alternating 30 current motor, of an armature, of means constructed to effect commutation electro-magnetically, and of two primary cores provided with energizing coils arranged in inductive relation to said armature, the said 35 energizing coils on each of the said primary cores being suitably arranged and connected in series with the coils on the other of said primary cores, as set forth.

44. The combination in an alternating 40 current motor, of an armature, of means constructed to effect commutation electro-magnetically, of two individual primary cores provided with energizing coils so arranged that the coils on the first of said cores have 45 a quadrature relation to the coils on the second of said cores, and the coils on one primary core connect in series with those on the other of said primary cores, as set forth.

50 45. The combination in an alternating current motor, of an armature, an impedance commutator, and of two individual primary cores provided with energizing coils so arranged that the coils on the first 55 of said cores have a quadrature relation to the coils on the second of said cores, the coils on one core being connected in series with those on the other core, as set forth.

46. The combination in an alternating 60 current motor, of a secondary element, of means constructed to effect commutation of the electric currents induced in the secondary element electro-magnetically, and of a primary element consisting of two individual cores wound with coils; electrical

connection whereby the coils of two primary cores may be energized by currents having the same phase, the primary coils being constructed and arranged to promote magnetic fields in the first core in quadrature with 70 the magnetic fields in the second core, as set forth.

47. The combination in an alternating current motor, of a common terminal, a primary element, a secondary element, the secondary element consisting of a core and of secondary or armature coils wound thereon, impedance coils tapped into and connecting said armature coils to said common terminal, and short-circuited coils arranged in 80 inductive relation to the impedance coils in certain predetermined fixed positions relative to said primary element, as set forth.

48. In an alternating current motor, the combination of two primary core rings, a 85 secondary core ring, an inducing circuit wound on one of the primary core rings, an energizing circuit wound on the other of the primary core rings, the inducing circuit being connected in series with said energizing 90 circuit, and being so arranged that the magnetic poles created by said inducing circuit will be in quadrature or other displaced relation with the magnetic poles created by the energizing circuit, a common terminal, 95 an induction circuit wound on the said secondary core ring, and provided with junction points, impedance coils connecting the junction points of the coils of the said induction circuit to said common terminal, 100 and short-circuited windings placed in inductive relation to the said impedance coils in certain predetermined fixed positions relatively to said primary core rings, as set forth.

49. In a single-phase alternating current motor, the combination with an armature of a field energizing circuit and a primary inducing circuit, the primary inducing circuit being arranged in close inductive relation 110 with the armature and connected in series, and superposed in quadrature upon the energizing circuit, a common terminal, and tapped circuits on said armature containing impedance coils terminating in said common 115 terminal, as set forth.

50. In a single-phase alternating current motor, the combination of a primary element and a secondary element, a primary field energizing circuit, a primary inducing 120 circuit, secondary impedance coils, and secondary inductors, the primary inducing circuit being arranged in close inductive relation with the secondary element and connected in series and superposed in quadrature upon the primary field energizing circuit, the secondary impedance coils and inductors being constructed and arranged to reverse the direction of flow of currents induced in the conductors of the secondary 125 130

element with reference to the direction of flow of currents in the conductors of the primary element at predetermined points in the revolution of the secondary element, as set forth.

51. In a single-phase alternating current motor, the combination of a primary element and a secondary element, a primary field-energizing circuit, a primary inducing circuit, secondary impedance coils, and secondary induction coils, the primary inducing circuit being arranged in close inductive relation with the armature and connected in series and superposed in quadrature upon the primary field energizing circuit, the secondary impedance coils, and the secondary induction coils having short-circuited windings, all constructed and arranged to reverse the direction of flow of currents induced in the conductors of the secondary element with reference to the direction of flow of currents in the primary conductors at predetermined points in a revolution of the secondary element, as set forth.

52. In a single-phase motor, the combination of a primary element and a secondary element, a primary field-energizing circuit, a primary inducing circuit, secondary impedance coils, secondary induction coils, and secondary inductors, the primary inducing circuit being arranged in close inductive relation with the secondary element and connected in series and superposed in quadrature upon the energizing circuit, the secondary impedance coils, the induction coils having short-circuited windings, and the inductors being constructed to reverse the direction of flow of the currents induced in the secondary conductors with reference to the direction of flow of currents in the primary conductors at predetermined points in a revolution of the secondary element, as set forth.

53. In an alternating current machine, the combination of a common terminal, an armature having a winding provided with commutation leads, impedance coils arranged in said leads and connecting the armature coils with said common terminal, and means constructed and arranged to collectively short-circuit said leads upon one another at points between said armature coils and impedance coils, whereby the impedance coils are made to perform the same function as the armature coils, when the machine is operated as an induction motor, as set forth.

54. In an alternating current machine, the combination of a primary element, primary field coils, and primary pole-face coils connected in series with the said primary field coils, a common terminal, an armature arranged in inductive relation to the said pri-

mary element, and carrying coils provided with leads, impedance coils introduced in said leads and connecting the coils of said armature to said common terminal, means constructed to reverse the direction of flow of current through certain of the primary pole face coils so that they act with the primary field coils to produce magnetic poles of maximum intensity, and means constructed to collectively short-circuit said leads upon one another at points between said armature coils and impedance coils, whereby the impedance coils are made to perform the same function as the armature coils when the said machine is operated as an induction motor, as set forth.

55. In an alternating current machine, the combination of a primary element, primary field coils, primary pole-face coils connected in series with the said primary field coils, an armature arranged in inductive relation to the said primary element and carrying coils provided with leads, impedance coils introduced in said leads and connecting the coils of said armature to said common terminal, and means constructed to reverse the direction of flow of current through certain of the primary field coils so that they act with the primary pole-face coils to produce magnetic poles of maximum intensity, as set forth.

56. The combination in an electric motor, of a field element, field coils and pole-face coils connected in series, an armature element, armature coils provided with commutation leads, a commutation ring, impedance coils arranged in the commutation leads and made to terminate in said commutation ring, induction coils having short-circuited windings arranged in inductive relation at predetermined points to said impedance coils, inductors arranged in predetermined positions with reference to said impedance coils and induction coils, means constructed to change the direction of the flow of current in the said pole-face coils, whereby the direction of rotation of the armature element relatively to the field element of the said motor is reversed, as set forth.

57. The combination in an electric motor, of a field element, field coils and pole-face coils connected in series, an armature element, armature coils connected and arranged with commutation leads, a commutation ring, impedance coils arranged in the commutation leads and made to terminate in said commutation ring, induction coils having short-circuited windings arranged in inductive relation at predetermined points to said impedance coils, inductors placed in predetermined positions with reference to said impedance coils and induction coils, and means constructed to change the direction of flow of the current through the said field coils, whereby the direction of rotation of the

armature element relatively to the field element of the said motor is reversed, as set forth.

58. The combination in an electric motor, 5 of a primary element consisting of two core rings, primary field coils wound on one of the said rings, the primary pole-face coils wound on the other of the said rings and connected in series with said field-coils, a 10 secondary armature element arranged in inductive relation to both rings of said primary element, armature coils provided with commutation leads, a commutation ring, impedance coils arranged in the commutation 15 leads and made to terminate in said commutation ring, induction coils having short-circuited windings arranged in inductive relation at predetermined points to the impedance coils, and inductors arranged in 20 predetermined positions with reference to said impedance coils and induction coils, as set forth.

59. In an electric machine, the combination with a primary element and a secondary 25 element, of means whereby secondary currents, electro-magnetically commutated at starting, perform their function uncommutated at speed.

60. In an electric machine, the combination with a primary element and a secondary element, of means whereby rotation is effected at starting by currents commutated electro-magnetically, and of means whereby, 35 during a predetermined acceleration, the secondary currents react uncommutated in maintaining or increasing the speed, as set forth.

61. In an electric motor, the combination of a primary element, of a secondary element, and of means whereby impedance coils, short-circuited elements, and inductors are made effective in starting an accelerating rotation of said motor up to predetermined speeds, and means whereby said 40 impedance coils, short-circuited elements, and inductors are eliminated at speeds exceeding said predetermined speeds, as set forth.

62. The combination in an electric machine, of an armature and armature coils 50 connected in a closed winding and of tapped circuits therefrom terminating in a common terminal and of means whereby said tapped circuits are made inductive at starting, and of means whereby said tapped circuits are 55 made non-inductive at speed, as set forth.

63. The combination in an electric machine, of an armature and armature coils connected in a closed winding and of tapped circuits therefrom each containing self-in-

duction, and of means whereby the self-induction of each individual tapped circuit is suppressed in succession at predetermined points in a revolution of the armature at starting and when speeding up, and of means whereby the self-induction of the individual tapped circuits are collectively suppressed at a predetermined speed, and of means for reversing the direction of rotation of the armature, as set forth.

64. The combination in an electric machine, of a primary element and a secondary element, and of tapped circuits from the secondary element, each being connected to a common terminal and containing self-induction, and of means whereby at starting 70 and when speeding up the self-induction is suppressed in each of the tapped circuits in succession at predetermined points in a revolution of the secondary element, and of means whereby at a predetermined speed the 75 self-induction is continuously suppressed in a predetermined number of the individual tapped circuits, so as to cause the secondary to be influenced thereafter by currents of a predetermined number of phases and the 80 electric machine to operate as an induction motor, as set forth.

65. In an electric machine, in combination with field coils and pole face coils, armature coils connected in a closed winding, a common 90 terminal, leads having self-induction connecting said armature-coils with said common terminal, and short-circuited coils arranged in inductive relation to said leads, as set forth.

66. In an electric machine, the combination with a primary element, of armature coils connected in a closed winding, impedance coils, and means whereby the inductance of said impedance coils, with respect 100 to the current of the secondary circuit is cut down during commutation, as set forth.

67. In an electric machine, the combination with field coils and pole face coils, of armature coils connected in a closed winding 105 and unconnected with said field coils and pole face coils, a common terminal, impedance coils connecting the armature coils with said terminal, and means whereby the effectiveness of said impedance coils is changed at 110 predetermined points in the revolution of the armature, as set forth.

In testimony whereof, I affix my signature, in the presence of two subscribing witnesses.

WINDER ELWELL GOLDSBOROUGH.
